UNITED STATES PATENT OFFICE

2,599,077

ROTARY TOOL FOR SCRAPING TUBE
INTERIORS

Charles E. Sturgis, Rochester, N. Y.

Application September 4, 1948, Serial No. 47,811

3 Claims. (Cl. 15—104.19)

1

This invention relates to an adjustable and refillable reamer type cleaning tool.

In applicant's prior Patent 2,020,442, granted November 12, 1935 there is disclosed a cleaning tool that is adjustable to clean various sized bores, the interior of bushings as well as slots or oil grooves.

The present invention has for its purpose the production of an improved cleaning tool of such construction that it is sturdy and reliable in operation and can be manufactured at reduced cost over prior devices.

The various features and advantages of the invention will appear from the detailed description and claims when taken with the drawings in which:

Fig. 1 is a view of the improved cleaning tool of the present invention;

Figs. 2 and 3 are longitudinal sections of the tool shown in Fig. 1, illustrating several different adjustments of the tool adapting it for use in bores of various sizes;

Fig. 4 is a fragmentary view of the free end of the stem;

Fig. 5 is a longitudinal section of a thimble to cooperate with the free end of the stem;

Fig. 6 is a transverse view of the tool taken substantially on the line 6—6 of Fig. 3;

Fig. 7 is a side view of one of the coiled cleaning elements of the tool;

Fig. 8 is a longitudinal section of a modified form of one of the coiled cleaning elements; and

Fig. 9 is a fragmentary elevation partially in section, illustrating a modified construction for connecting the handle to the sleeve of the tool.

In the drawings, the reference character 5 designates a metal stem in the form of a rod which is tapered to a rounded end 6 at its upper portion (Figs. 1, 2, 3 and 4). In spaced relation to the rounded end 6, the stem is provided with a peripheral groove 8 substantially at the junction of the tapered end with the main part of the stem. This groove cooperates in securing a metal retaining thimble 9 on the upper end of the stem. The upper or closed end 10 of the thimble, which is generally rounded and knurled externally, is apertured to receive the upper part of the stem. The thimble is made with an internal annular shoulder 12 of such diameter that it will force a split retaining ring 13 into the annular groove 8 in the stem. The ring 13 while in the groove 8 engages the shoulder 12 to prevent the thimble from being forced off of the rounded end of the stem while the thimble is being staked to the stem, the staking being indicated at the points 11.

2

The major portion of the thimble is spaced from the stem providing an annular recess to receive the upper ends of a series of cleaning elements 14 each comprising a spirally wound coil 5 of metal or the like, such as instrument wire. The lower ends of these elements are received within a similar annular space between a second metal thimble 15 and the stem on which the thimble 15 is freely slideable. The closed end of 10 the thimble 15 is cone-shaped at 16 with a knurled surface for a purpose to be described.

The lower end of the stem 5 is threaded at 17 so that an internally threaded sleeve 18 can be screwed thereon. The sleeve 18, when screwed 15 on the stem 5, forces the thimble 15 and in turn the lower ends of the elements 14 in the direction of the round end of the stem until their intermediate portions bulge outward to the respective positions illustrated in Figs. 2 and 3 for use 20 in bores of various diameters.

It will be understood that the sleeve 18 can be unscrewed on the stem thereby releasing the thimble 15 until the intermediate portions of the elements 14 lie in parallel relation against 25 the stem. Further release of the thimble enables the elements 14 to be removed from the unit for cleaning or replacement. The cone-shaped portion 16 of the thimble 15 with the knurled surface thereon, mates in locking relation with 30 the dished upper surface 20 of the sleeve 18. This sleeve is externally knurled at 21 (Fig. 1) to facilitate screwing the sleeve 18 on and off of the threaded lower end of the stem 5.

The unit just described is used with a handle 35 22 in the form of a shaft which is internally threaded at 23 so that it can be screwed on the threaded portion 17 of the stem 5. It should be pointed out that the handle is screwed on the threaded end of the stem 5, until its upper end 40 (Figs. 2 and 3), telescoped into the recess 18a in the sleeve 18, snugly engages the inner surface of the sleeve. This arrangement provides a rigid connection between the handle and the tool proper. The mating surfaces of the thimble 15 and the sleeve 18 engage each other so securely, 45 due to the knurling on one of these surfaces, that the thimble is securely retained in a given position of adjustment. Thus the diameter of the intermediate portions of the elements 14 will not change substantially when they have once 50 been adjusted.

In Fig. 8, there is illustrated a modified form of cleaning element comprising a coil of instrument wire through which there extends a core 25 of instrument wire or the like. This construction permits the coil to be made of smaller diameter

and yet the cleaning element will possess the desired degree of rigidity. The core is slightly longer than the coil.

In certain cleaning tools of smaller size, it has been found desirable to attach the handle 22 to the cleaning unit in accordance with the modified construction shown in Fig. 9. In this construction, the sleeve 18 instead of being provided with a recess 18a as in Figs. 2 and 3, is provided with a tongue 26 (Fig. 9). This tongue telescopes into the recess 27 formed in the upper end of the internally threaded handle. The adjustment of this modified form of cleaning tool will be the same as that already described.

The tool of this invention may be used alone or in combination with a cleaning cloth. Where a cleaning cloth is utilized, the piece of cloth is provided with a central opening therein of such a size that it will just receive the free end 6 of the stem 5. The cloth, while engaging the thimble 10, is wrapped around the unit to which it clings even when the tool is moved back and forth in a bore.

What I claim is:

1. In a cleaning tool, a stem having a peripheral groove near one end thereof and a threaded portion at its other end, a primary thimble and a secondary thimble in spaced relation on said stem and defining therewith annular spaces opening toward each other, a plurality of elongated resilient cleaning elements having their respective ends retained in said spaces, the primary thimble being located adjacent said groove having an internal shoulder facing toward the adjacent end of said stem, a ring located in said groove and projecting in the path of the shoulder on the primary thimble whereby said thimble is prevented from being forced off of the adjacent end of the stem, said secondary thimble being free to slide and rotate on said stem, and a sleeve threaded on said stem for adjustment thereon into engagement with the secondary thimble, the sleeve and the secondary thimble having mating surfaces at least one of which is roughened to bite into the other surface whereby the secondary thimble and sleeve are locked in adjusted position on the stem.

2. In a cleaning tool, a stem having a peripheral groove near one end thereof and a threaded portion at its other end, a primary thimble and a secondary thimble in spaced relation on said stem and defining therewith annular spaces opening toward each other, a plurality of elongated resilient cleaning elements having their respective ends retained in said spaces, the primary thimble being located adjacent said groove having an internal shoulder facing toward the

adjacent end of said stem, a ring located in said groove and projecting in the path of the shoulder on the primary thimble whereby said thimble is prevented from being forced off of the adjacent end of the stem, said primary thimble being permanently anchored to said stem, said secondary thimble being free to slide and rotate on said stem, and a sleeve threaded on said stem for adjustment thereon into engagement with the secondary thimble, the sleeve and the secondary thimble having portions nesting one within the other with mating surfaces thereon at least one of which is knurled whereby the secondary thimble and sleeve are locked in adjusted position on the stem.

3. In a cleaning tool, a stem having a threaded portion at one end, a primary thimble and a secondary thimble in spaced relation on said stem and defining therewith annular spaces opening toward each other, a plurality of elongated resilient cleaning elements having their respective ends retained in said spaces, the primary thimble being located adjacent the unthreaded end of said stem, the inner surface of said primary thimble adjacent said stem being staked to said stem, said secondary thimble being free to slide and rotate on said stem, and a sleeve threaded on said stem for adjustment thereon into engagement with the secondary thimble, the sleeve and the secondary thimble having conical mating surfaces at least one of which is roughened to bite into the other surface whereby the secondary thimble and sleeve are locked in adjusted position on the stem.

CHARLES E. STURGIS.
